UNITED STATES PATENT OFFICE.

JOSEPH MENCHEN, OF NEW YORK, N. Y.

LENS-BOX.

SPECIFICATION forming part of Letters Patent No. 761,977, dated June 7, 1904.

Application filed December 15, 1903. Serial No. 185,216. (No model.)

To all whom it may concern:

Be it known that I, JOSEPH MENCHEN, a citizen of the United States, and a resident of the city, county, and State of New York, have invented certain new and useful Improvements in Lens-Boxes, of which the following is a specification.

My invention relates to what are known to the trade as "lens-boxes," which are used to project certain lights or scenes upon screens or stage-settings, and has for its object the combining with a lens-box of a stereopticon, kaleidoscope, or other optical appliance which may prove useful in scenic effects, and provides means for the instant attachment or release of these adjuncts. These and other objects of my invention will be more fully described in the following specification, and set forth in the appended claims.

20 In the drawings forming a part of this specification, and in which like reference characters refer to like parts, Figure 1 is a side view of a lens-box with a stereopticon applied thereto. Fig. 2 is a longitudinal sectional view of 25 the lens and coupling-rings in position. Fig. 3 is a side view of these rings detached. Fig. 4 is a front view of the slide-ring in its place on the front of the box.

In the use of lights for stage effects the same 30 are usually inclosed in an upright box 1 and adjusted or extinguished by suitable thumbscrews and switch-levers, the box being mounted on the horizontal arm of a standard 2 and adapted to be swung in a vertical arc 35 thereon by the thumb-wheel 3, and the cylindrical section 4 of the box may be provided with an opening 5 for the inspection of the lamp by the operator. The standard 2 also permits of the rotation of the box on a horizontal plane. On the front wall of the box, 40 concentric with the cylindrical part 4 thereof, is a lens-holding ring 6, riveted or otherwise fastened and having upper and lower horizontal guideways 7 and carrying lens 8. 45 This lens 8 is adapted to throw upon a stage-setting what are known as "flood-light" and "spot-light"—i.e., a light diffused over a large area or one concentrated within small limits.

50 A ring 9, carrying a lens 10 and having

guide-rails 11, which slide in the ways 7, is provided for use in connection with a stereopticon or the like. The outer surface of this ring 9 receives and supports a flanged ring or collar 12, carrying set-screws 13, which 55 clamp it to the ring 9 after being set at any desired point around its periphery. The flange 14 of this collar has two bosses 15, which carry the horizontal rods 16, to the front ends of which are secured the bellows 60 17 and the tube 18, carrying the objective-lens. The front wall 19 of the bellows has bosses 20, in which the rods 16 are secured, and the rear partition 21 has bosses 21^a, through which slide the rods 16 to permit of 65 the adjustment of the bellows and the objective-lens. The wall 21 carries a yielding partition 22, with threaded rods 24, carrying the springs 25, which are compressed between the wall 21 and the partition 23 by the nuts 26. 70 Between the flange 14 and the partition 22 is placed and held kaleidoscopic or illustrated slides or colored screens.

The operation of the box and the attachments is as follows: As hereinbefore explained, the lens 8 when used alone is designed to produce a diffused or concentrated light on the stage or scene, accordingly as the light in the box 1 is near to or removed from the lens. To produce stereopticon effects, however, two 80 lenses are required, and for this purpose it has heretofore been necessary to use two lamps. Stereopticons require a large and costly lamp-box, and the two lamps would not only be expensive, but occupy much valuable space. 85 By providing the stereopticon attachment with the collar 12 and clamping the latter to the ring 9 I am enabled to instantly slide the ring into its position on the front of the ring 6, making one lamp serve the purpose of 90 throwing spot and flood lights as well as giving stereopticon and kaleidoscopic effects. The annular coupling of the ring and collar permits of the rotation of the stereopticon to any inclination from the perpendicular that 95 may be desired and the screws 13 set to hold it at the desired angle.

It is obvious that I may apply and secure the collar 12 to the ring 9 while the latter is already in its position on the ring 6 or before 100

the same has been mounted thereon. When the stereopticon is properly attached, the objective-lens 18 may be adjusted by sliding it, with the rods 16, in or out the bosses 15 until 5 the proper focus is obtained.

What I claim, and desire to secure by Letters Patent, is—

1. In a lens-box the combination of the box, guideways thereon, a flanged ring adapted to 10 slide in the guideways, and a collar telescoping with the ring and adapted to be adjusted circumferentially about the same, substantially as described.

2. In a lens-box the combination of a box, 15 a ring carrying a lens secured to the box and having guideways, a ring carrying a second ring and having flanges adapted to slide in the guideways and a collar adapted to be fitted on the second ring and carrying a stereopticon, substantially as described.

3. In a lens-box the combination of a box, 25 a ring with a lens secured to the box, a second ring with a lens adapted to be coupled to the first ring, means for coupling the two rings, a flanged collar adapted to be secured to the second ring, adjustable rods adapted to move through the flange at a right angle to the axis of the lenses and a stereopticon carried by the outer ends of the rods, substantially as described.

4. In a lens-box, the combination of a box, 30 a ring secured to the box and carrying a lens, a ring carrying a second lens and adapted to be coupled to the first ring, a collar adapted

to fit the second ring and be adjusted concentrically thereon, set-screws, a flange with bosses on the collar, rods passing through the bosses, a stereopticon on the outer ends of the rods and a resilient frame at the inner end of the stereopticon adapted to coöperate with 40 the flange of the adjustable collar, substantially as described.

5. In a lens-box, the combination of a box, a ring secured thereto and carrying a lens, a second ring with a lens adapted to be coupled 45 to the first lens, means for coupling the two rings, a flanged collar adjustably secured to the second ring, bosses on the flange of the collar, rods adjustable in the bosses, a stereopticon, a frame secured to the front ends of 50 the rods and carrying the objective lens and the front end of the bellows of the stereopticon, a second frame carrying the rear end of the bellows and having perforations, a third frame having springs carrying adjusting-screws which play through the perforations 55 of the second frames and adapt it to be adjusted with relation to the flanges of the adjustable collar and thumb-nuts to adjust the position of the third frame and the tension of 60 its springs, substantially as described.

In witness whereof I have hereunto set my hand in presence of two witnesses.

JOSEPH MENCIEN.
